UNITED STATES PATENT OFFICE

WALTER O. SNELLING, OF ALLENTOWN, PENNSYLVANIA

PERFUME

No Drawing.

Application filed February 13, 1928. Serial No. 253,846.

My invention relates to improvements in perfumes and more particularly relates to providing an improved volatile vehicle for perfumes, such vehicle having advantageous properties as compared with alcohol as now commonly used.

The use of alcohol as a vehicle for perfumes is very old, and even in the very early days of the perfumers' art odoriferous constituents were extracted by means of alcohol, and the alcoholic tincture or extract was used directly as a perfume. With the development of "synthetics" and the discovery of methods of obtaining perfume "absolutes", the use of alcohol as the vehicle still persisted, and in general was so satisfactory that the use of other materials was given little or no consideration. At the present time, however, with grain alcohol subject to such restrictions as to distribution and use as to make the obtaining of the material of proper purity a matter of difficulty, and the cost of the material being very high, even when material of proper quality can be obtained, the development of a satisfactory substitute is a matter of considerable economic importance.

I have discovered that the heavier volatile hydrocarbons present in natural gas may be condensed and purified to give a liquid product free from objectionable odor, and having in fact a sweet and pleasant odor blending readily with the odoriferous materials commonly used in the manufacture of perfumes. Particularly when used in combination with perfume essences and fixatives such as benzyl benzoate, benzyl cinnamate, methyl anisate, benzyl iso-eugenol and phenyl ethyl phenylacetate. I find that my new products give perfumes of superior quality to similar perfumes made from grain alcohol.

By "perfume essence" as used in this specification, I refer to the pleasant odoriferous perfume bases commonly used in the prep-

aration of perfumes, including both perfume materials obtained from natural sources and the synthetic substances prepared by chemical processes. By "fixatives" I refer to the substances commonly used in the perfumers' art to control the volatility of the constituents of the perfume essence, and I wish to include under fixatives both inodorous fixatives used wholly for the purpose of controlling volatility, and odoriferous fixatives which in addition to controlling the volatility of the perfume base also impart odor to the finished perfume.

In the preparation of my preferred product for use as a vehicle in perfumes, I may obtain liquid condensates from natural gas by any of the usual methods such as compression and cooling, absorption in heavy mineral oil, absorption by means of activated carbon, or the like, and I then separate by distillation and rectification the portion of the liquid condensate boiling between 30° C. and 100° C. To further purify the condensate so obtained, I prefer to treat it with some form of active carbon such as Norite or the like, several treatments with decolorizing carbon being given if necessary, until complete freedom is obtained from any unpleasant odor, and the product is either inodorous or has only a sweet, ethereal smell.

The product which I obtain, upon the completion of my condensing and refining steps, has a vapor pressure of less than 200 millimeters of mercury at 0° C., but has a vapor pressure in excess of 100 millimeters of mercury at 80° C. All material outside of this vapor pressure range should preferably be excluded, as hydrocarbons having a vapor pressure of more than 200 millimeters of mercury at 0° C. are too volatile for use in ordinary perfumes, and hydrocarbons having a vapor pressure of more than 100 millimeters of mercury at 80° C. evaporate somewhat too slowly to be entirely satisfactory.

for commercial uses. In special cases, however, where either greater volatility or less volatility is desired than exists in the case of normal perfumes, I may employ purified natural gas hydrocarbons having a vapor pressure of somewhat more than 200 millimeters at 0° C., or having a vapor pressure of somewhat less than 100 millimeters at 80° C. 5 to a somewhat undesirable modification of the odor of the finished perfume.

I claim: 70

The new composition of matter comprising perfume essence and a liquid condensation product of natural gas having a vapor pressure of less than 200 millimeters of mercury at 0° C., but more than 100 millimeters of mercury at 80° C. 75

In testimony whereof, I have hereunto subscribed my name this 10th day of February 1928. 80

WALTER O. SNELLING. 85

Very careful tests of the product made in accordance with the present invention have shown it to possess properties even more desirable than the properties of alcohol, and particularly in the manner in which the vehicle volatilizes, and the manner in which its sweet and ethereal odor blends with the more delicate odors used in modern perfumery; the product has been found to be not only a satisfactory substitute for the highest grades of refined alcohol, but to be even much superior to such alcohol. Although my improved natural gas product may be used in perfumes with alcohol, up to the limits of mutual solubility of the two products, such admixture is not necessary, and in some cases is undesirable, the pure hydrocarbon product being a satisfactory solvent for most perfume essences and fixatives, and giving very desirable perfumes when constituting up to 90% or even more of the finished perfume, the remainder of the material being the perfume essence and the fixative. 90 95 100 105 110 115 120

I do not claim as any part of my invention the use of gasoline or of petroleum ether, a product obtained from gasoline by distillation or rectification, as experience has shown that these hydrocarbon products contain very minute amounts of highly odoriferous materials which, on evaporation of the main quantity of the liquid, leave a residual distinctive and unpleasant odor making their use undesirable for perfume purposes. My invention is limited to the use, as a vehicle in perfumes, of a liquid condensate from natural gas having a vapor pressure of less than 200 millimeters of mercury at 0° C., but having a vapor pressure of more than 100 millimeters of mercury at 80° C. 125

It will be evident that many modifications may be made, without departing from the essential features of my invention as herein disclosed. The flammability of my perfume vehicle may be reduced by the admixture of chlorinated hydrocarbons, although for ordinary use this is not necessary, and leads
